(57) **CLAIM**

We claim the ornamental design for a drive-up financial transaction machine, as shown and described.

DESCRIPTION

FIG. 1 depicts a front perspective view of a drive-up financial transaction machine.

FIG. 2 depicts a front elevational view thereof.

FIG. 3 depicts a back elevational view thereof.

FIG. 4 depicts a left side elevational view thereof.

FIG. 5 depicts a right side elevational view thereof.

FIG. 6 depicts a top plan view thereof; and,

FIG. 7 depicts a bottom plan view thereof.

The broken lines in the drawings illustrate environmental structure on the article and form no part of the claimed design.

1 Claim, 5 Drawing Sheets
